UNITED STATES PATENT OFFICE.

LEWIS EMMETT JAHNS, OF MORTON GROVE, ILLINOIS.

GOLF SAND-TEE MOLDER.

Application filed May 7, 1927. Serial No. 189,715.

The object of this invention is to make golf sand tees of uniform size and height in different heights.

5 *Description of the several views of the drawing.*

Figure 1 is a view of the molder.

Figure 2 is a view of the key set in the upper position.

10 Figure 3 is a view of the key set in the lower position.

Figure 4 is a view of the slotted insert that fits in the tube in the plunger. The head of the key fits under this insert in the lower position and above in the upper position. It is slightly thinner on the side 15 opposite the slot.

Figure 5 is a view of the key with the convex button which is attached to the lower 20 end.

Detailed description of the invention.

The invention consists of a bell shaped cup open at the larger end, with a cylinder 25 extending on the top, and a shoulder extending around the lower part of the outside of the cylinder, the cup having a round hole in the center of the roof slightly smaller than the inside of the cylinder, all this 30 made in one piece of metal or composition.

Working in the cylinder is a plunger consisting of a tube open at the top and with a small key hole in the bottom, inserted in this tube is a snug fitting slotted insert, 35 slightly thinner on the side opposite the slot, the lower part of the inside of the tube being slightly less in diameter slightly higher than the height of the key head prevents this insert from going to bottom 40 of tube, on the head of the tube a cap is fastened, a wire coil spring fits around the tube, the top of the spring resting on the bottom of the cap, the lower end on the roof of the cup.

45 To operate to make sand tee, pack cup with moist sand, holding tee molder bottom down just off ground and press down on cap.

I claim:

50 1. A golf sand tee molding or forming device adjustable for making or molding sand tees in two different heights consisting of a molding bell shaped cup with a cylinder extending on the upper and small 55 part of the cup, and a shoulder extending

around the out side of the lower end of the cylinder, the upper part of the molding bell shaped cup being centrally perforated, said perforation being less than the inside diameter of the cylinder, and a hollow tube, said hollow tube on one end tapered on the inside and key holed through and capped on the other end, said hollow tube surrounded by a coil spring resting on the bottom of the cylinder and against the cap, said hollow tube containing a small cylindrical insert slotted for movement of key head, said insert being thinner on side opposite key head slot, said insert being snugly fitted on inside of hollow tube in tapered inside, said hollow tube having movement in cylinder and through centrally perforated hole in top of molding cup, and a convex button with a key extending from the center of one side of said button, head of said key fitting into key hole at bottom of said hollow tube and said key having movement below, through and above small cylindrical slotted insert in hollow tube, said convex button having positions in upper part of molding cup or movement in molding cup in connection with movement of cap, tube and key. 70

2. A golf sand tee forming or molding device having a push plunger having movement through cylinder head of forming cup through centrally perforated top of molding cup and into molding cup, said plunger consisting of a hollow tube capped on one end tapering on inside of other end and key holed through, resting on inside tapered end of the tube a small cylindrical insert key holed through, said hollow tube being surrounded by a coil spring resting on bottom of cylinder and top against cap, and a button having a key attached on center of one side, said key fitting and having movement in key hole of said hollow tube in plunger, and said key having movement under, through and above said small cylindrical insert in tube, said button at end of key having 100 positions in upper part of molding cup, and having movement in connection with raising or lowering of plunger, said attached key and button having disconnection by movement of key through key hole in bottom of tube in said plunger.

In testimony whereof, I have signed my name to this, at Morton Grove, Illinois, this 31st day of May, 1927.

LEWIS EMMETT JAHNS.
